TAPE CUTTER

Irvin J. Gershen, Hillside, N. J., assignor to Industrial Tape Corporation, a corporation of New Jersey

Application April 7, 1953, Serial No. 24,393

Term of patent 14 years

(Cl. D74—1)

To all whom it may concern:

Be it known that I, Irvin J. Gershen, a citizen of the United States of America, residing in Hillside, county of Union, State of New Jersey, have invented a new, original, and ornamental Design for a Tape Cutter, of which the following is a specification, reference being had to the accompanying drawing, forming part thereof, wherein:

Fig. 1 is a side view of a tape cutter showing my new design;

Fig. 2 is a rear end view thereof;

Fig. 3 is a sectional view along the lines 3—3 of Fig. 2;

Fig. 4 is a front end view;

Fig. 5 is a top plan view;

Fig. 6 is a bottom plan view; and

Fig. 7 is an isometric view thereof.

The fragmentary dotted lines representing a roll of tape as seen in Fig. 1 are only for the purpose of illustration.

I claim:

The ornamental design for a tape cutter, substantially as shown and described.

IRVIN J. GERSHEN.
